C. F. SCARBOROUGH,
BOTTLE CAP REMOVER AND ALARM.
APPLICATION FILED JULY 12, 1918.

UNITED STATES PATENT OFFICE.

CHARLES F. SCARBOROUGH, OF MOUNT GILEAD, NORTH CAROLINA.

BOTTLE-CAP REMOVER AND ALARM.

1,307,519.

Specification of Letters Patent. Patented June 24, 1919.

Application filed July 12, 1918. Serial No. 244,561.

To all whom it may concern:

Be it known that I, CHARLES F. SCARBOROUGH, citizen of the United States, residing at Mount Gilead, in the county of Montgomery and State of North Carolina, have invented certain new and useful Improvements in Bottle-Cap Removers and Alarms, of which the following is a specification.

This invention relates to an improved bottle cap remover and alarm, being particularly designed for use at stands selling soft drinks, and has as its primary object to provide an arrangement whereby the surreptitious removal of the cap of a bottle and the appropriation of a bottled drink will be prevented.

The invention has as a further object to provide a construction wherein, upon the application of the remover to the cap of a bottle, for removing the cap, the alarm will be sounded.

A still further object of the invention is to provide a construction wherein the remover will be equipped with arms formed to fit over a bottle cap to engage therewith for removing the cap and wherein upon the engagement of the arms with the cap, the cap will close a circuit through the said arms for sounding the alarm.

And the invention has as a still further object to provide a device of the above described character which will be particularly simple in construction and which will be adapted for general use as a bottle cap remover.

Other and incidental objects will appear as the description proceeds. In the drawings, wherein I have illustrated the preferred embodiment of the invention, and wherein similar reference characters designate corresponding parts throughout the several views:

Figure 1 is an elevation showing my improved bottle cap remover and alarm, the alarm being conventionally illustrated.

Fig. 2 is a plan view of the remover with the top section of the handle removed,

Fig. 3 is a transverse sectional view taken on the line 3—3 of Fig. 2 and showing the mounting of the cap engaging arms of the remover upon the handle, and

Fig. 4 is a transverse sectional view taken on the line 4—4 of Fig. 2 and showing the manner in which the circuit wires leading to

the alarm are connected with the cap engaging arms. 55

In carrying out the invention I employ a cap remover including a handle 10. This handle is, as particularly shown in Figs. 3 and 4 of the drawings, formed of mating sections 11 and 12 and may be constructed of hard rubber, wood, or other approved insulating material. The confronting faces of the sections are recessed to snugly receive coacting metallic cap engaging arms 13 and 14 respectively, which extend through the forward end of the handle and diverge toward their inner ends to enter recesses 15 formed at the junction of the handle sections. At points adjacent the forward end 70 of the handle, the arms 13 and 14 are provided with flattened portions 16 and loosely fitted through these flattened portions are screw bolts or other suitable fastening devices 17 which also extend through the sections of the handle and act to clamp the said sections together as well as secure the arms in position upon the handle. From the forward end of the handle, the outer end portion of the arm 13 is formed to provide 80 a curved cap engaging member 18 while the outer end portion of the arm 14 is formed to provide a curved cap engaging member 19 coacting with the member 18 to define a split loop adapted to engage over the cap 85 of a bottle in a manner well understood. Preferably, the member 18 is provided with spaced lugs 20 while the member 19 is provided with a similar lug 21 to coat with the bottle cap. At their inner ends the arms 90 13 and 14 are formed with reduced looped terminals 22 within the recesses 15. Extending through and connecting the sections 11 and 12 of the handle, preferably at a point between said recesses, is a screw bolt 95 or other suitable fastening device 23 similar to the fastening devices 17, and like fastening devices 24 extend through the handle sections at spaced points adjacent the rear end of the handle. The handle sections will thus be firmly clamped together to rigidly hold the arms 13 and 14 between the sections while, at the same time, the said sections may be readily disconnected. 100

At the rear end portion of the handle, the 105 confronting faces of the sections thereof are formed with a channel 25 which, at its inner end, is provided with branches 26

leading into the recesses 15 and snugly fitting within the said channel is a flexible conductor 27. The circuit wires of this conductor are, at their inner ends, led through 5 the channel branches 26 and are connected with the arms 13 and 14 by screw bolts or other suitable fastening devices 28 loosely fitted through the terminal loops 22 of the said arms. At their outer ends the circuit 10 wires are respectively connected one with one terminal of a suitably located alarm or annunciator 29 and the other with a battery or other approved source of electrical energy 30, while a wire 31 leads from the 15 battery to the other terminal of the alarm. Any approved type of alarm may be employed and for convenience, I have conventionally shown the use of an electric bell. As will now be seen, the cap engaging 20 members 18 and 19 of the cap remover are included in circuit with the alarm 29 and battery 30, which circuit is normally broken at the gap between the said members. However, when in the use of the cap remover, 25 the members 18 and 19 are applied to a bottle cap for removing the said cap, it will be seen that the metal of the cap will close the circuit between the cap engaging members for sounding the alarm. Since both 30 of the members 18 and 19 must be engaged with the cap in order to effect the removal thereof, I accordingly provide an arrangement whereby it will be impossible to displace the cap of a bottle without sounding the alarm. Accordingly, surreptitious removal of the cap of a bottled drink, at a 35 stand selling such drinks, will be rendered impossible without warning being given to the attendant.

Having thus described the invention, what 40 is claimed as new is:

1. A bottle cap remover including a handle, arms mounted upon the handle and insulated with respect to each other thereby, the said arms at their inner ends being 45 adapted for connection with a conductor including the arms in circuit with an alarm and being formed at their outer ends with coacting cap engaging members.

2. A bottle cap remover including a handle formed of mating sections, arms mounted between the sections and insulated with respect to each other by the handle, the said arms being adapted to be included in circuit with an alarm, means connecting the sections of the handle and clamping the arms therebetween, and coacting cap engaging members carried by the arms. 55

3. The combination with a bottle cap remover having coacting cap engaging members insulated with respect to each other and adapted to have a circuit closed therebetween by a cap engaged by the said members, of an alarm included in circuit with the said members. 60

4. The combination with a bottle cap remover, of an alarm electrically connected therewith and adapted to be energized upon the application of the remover to a bottle cap. 70

5. The combination with a bottle cap remover including coacting cap engaging members insulated with respect to each other, of an alarm included in circuit with said members. 75

In testimony whereof I affix my signature.

CHARLES F. SCARBOROUGH. [L. S.]
